ABELARDO LINARES, OF MARACAIBO, VENEZUELA

SCREW ADJUSTABLE MECHANISM

Application filed June 1, 1927. Serial No. 195,810.

My invention relates to improvements in screw adjustable mechanisms adapted to and embodied in a combination of elements providing a jack, or like tool, and it consists in 5 the combinations, constructions and arrangements herein described and claimed.

In accordance with the present invention and as a feature thereof, I have provided structural means combining a wrench structure with a support for its fixed jaw and a hanger or jacking element for its movable jaw to form a jacking mechanism separable into its component parts for shipment or storage.

15 An object of the present invention is the provision of a jacking mechanism having a support constructed to permit the jack to be based upon a ground or platform level or upon an intermediate point.

20 A further object of the invention is the provision of a jacking mechanism embodying novel screw operated means for effecting the jacking and unjacking operation.

Another object of the invention is the provision of a base support for the jacking mechanism adaptable to variable positioning of the jack for vertical or horizontal jacking movement and for variable angular positions 30 of the jack relative to its support enabling the jack to be employed in positions and under circumstances not heretofore possible.

A further object of the invention is the provision of a jacking mechanism comprising a plurality of separable cooperating elements which will permit the jack to be readily assembled and disassembled and permit shipment or storage thereof in compact assembly requiring relatively small shipping or storage space.

40 These and other objects and advantages will be more clearly apparent from the detailed specification following which is to be read in conjunction with the accompanying drawings forming part thereof and in which:

Figure 1 is a view in vertical section with certain of the parts left in elevation, of a jacking mechanism constructed in accordance with the present invention and positioned for vertical jacking movement.

Figure 2 is a horizontal sectional view through the jack base taken on line 2—2 of Figure 1.

Figure 3 is a detail perspective of a portion of the jack base seating the fixed jaw of the 55 wrench structure.

Figure 4 is a transverse longitudinal section through the handled operating head of the jacking screw.

Figure 5 is a perspective detail of the supporting plate of the jack standard.

Figure 6 is a fragmentary vertical section taken on the line 6—6 of Figure 2 and showing the pivotal connection of the clamping member of the base with the base plate section seating the fixed jaw of the wrench structure.

The invention provides, among other features, a set of cooperating parts combining to form a lifting jack and including in the assembly, a plurality of jack supporting means enabling the jack to be based on ground or platform or to be mounted on or secured to an intermediate support and adjusted thereon to position the jack at an angle thereto.

In carrying out the invention, provision is made of a wrench structure providing the relatively movable parts of the jacking mechanism and comprising a jaw 1 having a shank rigid therewith, said shank comprising a relatively large non-circular inner end portion 2 and a smaller circular outer end portion 3 which has its extreme end portion further reduced and screw-threaded at 4. The wrench also comprises a movable jaw 5 for cooperating with the jaw 1 and having a tubular shank 6 which is slidable on the relatively large portion 2 of the shank of the jaw 1 and extends a substantial distance beyond the outer end of the portion 2 of the shank of the jaw 1. The bore of the portion of the shank 6 that is disposed on the portion 2 of the shank of the jaw 1 when the jaws are closed may conform in cross section with the cross sectional configuration of the portion 2 of the shank of the jaw 1 so that the jaw 5 will be held against turning about the axis of the shank of the jaw 1 and the outer end portion of the shank 6 beyond the outer end of the

portion 2 of the shank of the jaw 1 may have its bore formed to be circular in cross section and provided with internal screw threads indicated at 7.

5 A tubular externally screw threaded adjusting screw 10 is rotatably supported on the relatively small circular portion 3 of the shank of the jaw 1 and at its inner end abuts a bearing washer 11 that is disposed on the 10 portion 3 of the shank of the jaw 1 against the shoulder that is produced at the outer end of the portion 2 of the shank of the jaw 1, the inner end portion of the screw 10 being in threaded engagement with the internally 15 screw threaded outer end portion 7 of the shank 6 of the jaw 5. The outer end portion of the screw 10 is enlarged diametrically to produce an integral ratchet wheel 12 having its periphery curved substantially convexly 20 transversely thereof and formed with a circumferentially spaced series of radial sockets 13. The screw 10 is retained on the portion 3 of the shank of the jaw 1 by a washer 14 which abuts the outer end of the screw and 25 a retaining nut 15. The retaining nut 15 engages the screw threaded extreme end portion 4 of the shank of the jaw 1 and is secured to the latter by a set screw 16.

It is manifest that rotation of the screw 10 30 in one direction about the axis of the shank of the jaw 1 will cause the jaw 5 to move toward the jaw 1 when the jaws of the wrench are open and that reversal of the direction of rotation of the screw 10 will cause a reversal 35 of direction of movement of the jaw 5 in respect to the jaw 1. A set screw 17 that is carried by the outer end portion of the tubular shank 6 of the jaw 5 may be tightened against the screw 10 to prevent accidental rotation of 40 the screw 10 and consequently to hold the jaw 5 in adjusted position in respect to the jaw 1.

A lever for operating the screw comprises a handle bar 19 and a head for embracing the 45 ratchet wheel 12. Said head comprises a section 20 which is integral with the handle bar and a cooperating section 21 having a short shank 22 adapted to fit in a laterally cut away portion 23 on the adjacent end of 50 the handle bar 19 and connected with the handle bar 19 by a transverse pivot element 24. A retaining ring 25 is slidable on the handle 19 to and from position to overlap the shank 22 and to then retain the shank 22 completely 55 in the cut away portion 23 of the handle 19 so that the sections 20 and 21 will be retained on the ratchet wheel 12 and will partially encircle the ratchet wheel 12. The sections 20 and 21 are curved transversely to 60 conform substantially to the transverse curvature of the peripheral portion of the ratchet wheel 12. The free end of the shank 22 and the adjacent wall of the cut away portion of the handle 19 are complementarily beveled so 65 as to produce a relatively large contact sur-

face between the handle 19 and the shank 22 when the shank 22 is completely disposed in the cut away portion 23 of the handle 19. The adjacent or abutting ends of the sections 20 and 21 likewise are complementarily beveled so as to fit neatly and firmly against each other when the sections 20 and 21 are closed as shown in Figure 2. When the ring 25 has been slid along the handle 19 out of engagement with the shank 22, the section 21 may swing away from the section 20 a distance sufficient to permit removal of the lever from the ratchet wheel 12.

The section 21 of the head of the lever is formed with an outwardly extending tubular boss 26 having a head 27 at its outer end formed with the laterally extending flange 28 or marginal edge portion and with a relatively small central opening 29 in axial alignment with a larger opening 30 in the section 21. An actuating pawl 31 extends slidably through the opening 30 and has a reduced rigid shank 32 which protrudes from the tubular boss 26 through the opening 29 in the head 27. The outer end portion of the shank 32 is threadedly engaged by an adjusting nut 33 having a laterally extending finger 34 formed with a bent end portion 35 in contact with the edge of the flange 28. A convexo-concave spring washer 36 having a notched edge is disposed on the shank 32 between the nut 33 and the head 27 of the boss 26 and limits the inward movement of the pawl 31 in response to the actuation of a compression spring 37 that is coiled about the shank 32 within the confines of the tubular boss 26.

The nut 33 can be tightened to expand the spring washer 36 more or less and thereby to permit the pawl 31 to move a greater or less distance toward the center of the head of the lever to respond to the actuation of the spring 37. The extending inner end of the pawl 31 is beveled as indicated and is adapted to enter into one of the sockets 13 in the ratchet wheel 12 when the sections 20 and 21 are closed so that swinging of the lever in one direction about the axis of the shank of the jaw 1 will cause the screw 10 to turn in the same direction on the shank of the jaw 1 and swinging of the lever in the opposite direction about the axis of the shank of the jaw 1 will not cause rotation of the screw 10 for the reason that the beveled face of the pawl 31 will contact with a side wall of the associated socket 13 and will ride out of such socket against the action of the spring 37 onto the periphery of the ratchet wheel 12. In moving the jaw 5 toward jaw 1, the lever will be arranged on the ratchet wheel 12 so that it will be effective to turn the screw 10 in the required direction. The lever then may be reversed on the ratchet wheel when it is desired to reversely move the jaws.

In accordance with the purpose of the invention, the fixed jaw 1 is formed with an

extension or crown 8 on its head (Figure 1) of somewhat reduced area which extension or crown is demountably seated in a supporting frame forming with the fixed jaw a base 5 for the jack structure. Such frame may comprise a clamp which includes a substantially U-shaped frame member 40 having a pair of substantially parallel arms 41 and 42, respectively. The free end portion of the arm 42 carries a clamping screw 43. The arm 41 is formed with an extending lug 45 at its free end. The lug 45 is rounded off transversely and is adapted to fit between a pair of spaced lateral ears 46 and 47, respectively, on a supporting block 48. The members 46, 45, and 47 are provided with aligned openings for the reception of a pivot pin 49, whereby the supporting block 48 will be pivotally connected with the arm 41 of the frame member 40, as shown to advantage in Figure 10. The supporting block 48 is formed with a seat at 50 in which the crown portion 8 of the jaw 1 of the wrench is adapted to fit snugly. A fastening screw 51 has its shank 20 threaded through an opening in a side wall of the seat 50 and can be tightened until the end portion of the shank enters and engages with a socket or depression 52 the adjacent side of the crown portion of the jaw 1, where- 25 by the jaw 1 will be secured firmly to the supporting block 48. The jaw 1 then will serve as part of the jack base with its shank 2 constituting a guide upon which the tubular shank 6 of the jaw 5 can be adjusted to- 30 ward and away from the jaw 1.

The supporting block 48 has a substantially flat base and is formed with extending edge portions 53 as clearly shown in Figure 3. These edge portions 53 are formed 40 with parallel ears 54 at the free end of the block 48 and at the outer sides of and up- standing from slots 55 in the edge portions 53 of the block. A substantially U-shaped extension 56 has a pair of arms 57 formed at 45 their extremities with forwardly extending lugs or ears 58 which extend into the slots 55 and are secured to the block 48 by aligned transverse pivot elements 59. The lugs 58 abut the edges 53 when the rear faces of the 50 arms and web of the extension 57—56—57 are flush with the flat base of the block. The block will then have a bearing surface of relatively great area on a flat supporting surface when the block and its extension are 55 disposed on such flat supporting surface as shown in Figure 1 for vertical jacking movement. The movable jaw 5 and its sleeve 6 mount and form part of the lifting mechanism of the jack. Cooperating with the jaw 5 and its shank is a jack standard 61 which is provided intermediate its length with a laterally extending integral retaining ring 62 that is adapted to be slipped over the upper end of the shank of the jaw 5 when the 60 screw 10 has been removed therefrom. The

standard 61 then may be moved downwardly until the lower end of the standard 61 rests on the adjacent face of the jaw 5 and a reduced extension 63 is disposed in a socket 64 in the jaw 5. At this time, the retaining 70 ring 62 will rest on the upper end of the shank 6 of the jaw 5 and the standard 61 will be returned on the shank 6 of the jaw 5 by reason of the engagement of a depending marginal flange 65 on the ring 62 with the upper end portion of the shank 6. The screw 10 and its operating lever then may be disposed on the shank of the jaw 1 in the manner hereinbefore described and as illustrated in Figure 1. 75

The standard 61 is formed with vertical channels, as at 66, in its opposite sides, such channels extending from the upper end of the standard 61 nearly to the lower end thereof. The standard 61 also has a vertical series of 80 spaced supporting lugs 67 at the side thereof which is opposite to the retaining ring 62. Each of the lugs 67 has an upper face 68 that is inclined slightly from the horizontal in its outward and upward direction and a lower face 69 which is inclined downwardly and inwardly at a relatively great angle with the horizontal. A vertically adjustable supporting member or step plate 70 has an inner edge portion formed at 71 to fit snugly against the standard 61 between adjacent lugs 67 and to rest and be supported by the underlying lug, the upper face of the inner edge portion 71 being beveled as indicated at 72 to conform to the inclination of the lower faces of the lugs 67. The inner edge portion of the supporting member 70 is provided at its opposite sides with a pair of integral retaining arms, as at 73, which straddle the standard 61 and have guiding and retaining lugs, as at 74, formed 85 on their inner faces for entering and engaging with the channeled portion 66 of the standard 61, whereby the supporting member 70 will be firmly maintained in any adjusted position on the standard 61 when the supporting member 70 is horizontal as shown in Figure 1. The retaining and guiding lugs 74 have their lower faces inclined as indicated at 90 75 parallel with the upper face 72 on the inner edge portion of the member 70 and spaced from the upper face 72 of the inner edge portion of the member 70 a distance slightly greater than the thickness of the lugs 67 and the adjacent walls of the channels of the standard 61 combined, whereby the supporting member 70 can be swung upwardly from the position shown in Figure 6 nearly to the vertical and the inner edge portion 71 of the supporting member then will clear the edges 95 of the lugs 67 and the supporting member can be moved vertically along the standard to any desired position and the supporting member 70 then will remain in such position when it has been released and permitted to fall to horizontal position. A cover plate 76 is se- 100

cured by a screw 77 to the upper end of the standard 61 so that its end portions will obstruct the upper ends of the channels 66.

The operation of the jacking mechanism will be clear and need only be briefly reviewed. In the position of the parts shown in Figure 1, the jack base is resting upon the ground or a platform or floor with the clamp 40 turned on its pivot 49 to be flat in the plane of the floor. Rotation of the screw 10 in one direction through the handled intermittently gripping ratchet head will cause the plate 70 to lift or jack up a structure such as the front axle 78, of a motor vehicle, and reverse rotation will lower said axle or other structure. Where the structure to be lifted moved is so positioned relatively to the ground or platform so that the jack base 48 cannot be used, an intermediate support may be engaged and clamped between the arms 41, 42 of the U clamp 40 through its clamping screw 43. The ears 46, 47 are joined by flat supporting surfaces permitting swinging movement of the clamp arms 41, 42 through an arc of approximately 180 degrees, so that the clamp may be engaged with a support and positioned at an angle to the base 48 thereby permitting the use of the jack in other than vertical lifting operations, such for example, as in horizontal position with the U clamp 40 engaging a transverse support as an anchorage.

Obviously, the invention is susceptible of embodiment in forms other than those which are illustrated in the accompanying drawings, and I therefore consider as my own all such modifications and adaptations thereof as fairly fall within the scope of the appended claims.

40 I claim:

1. In a mechanism of the character described, a wrench having a jaw provided with a shank, a second jaw having a tubular shank slideable on the shank of the first named jaw, a block having a seat for the partial reception of said first named jaw and adapted to support said wrench with the shanks thereof upright, a standard adapted to rest at its lower end on said second named jaw, a ring carried by said standard adapted to engage with said tubular shank to retain said standard on said tubular shank, said standard having a longitudinal series of spaced teeth, and a substantially flat supporting member having means slidably embracing said standard and having a portion adapted to be supported on any one of said teeth.

2. In a mechanism of the character described, a wrench comprising a jaw having a shank and a second jaw having a tubular shank slideable on said first named shank, a block engageable with said first named jaw for supporting the wrench with the shanks upright, a standard having a laterally extending retaining ring engageable with the

upper end portion of said tubular shank, said standard having a reduced lower end portion and said second named jaw having a socket in its upper end for the reception of said reduced lower end portion of the standard, and a work supporting member vertically adjustable on said standard. 70

3. In a mechanism of the character described, a wrench comprising a jaw having a shank and a second jaw having a tubular shank slideable on said first named shank, a block engageable with said first named jaw for supporting the wrench with the shanks upright, a standard having a laterally extending retaining ring engageable with the upper end portion of said tubular shank, said standard having a reduced lower end portion and said second named jaw having a socket in its upper end for the reception of said reduced lower end portion of the standard, and a work supporting member vertically adjustable on said standard, and a clamp pivotally connected with said supporting block. 75

4. In a mechanism of the character described, a wrench comprising a jaw having a shank and a second jaw having a tubular shank slideable on said first named shank, a block engageable with said first named jaw for supporting the wrench with the shanks upright, a standard having a laterally extending retaining ring engageable with the upper end portion of said tubular shank, said standard having a reduced lower end portion and said second named jaw having a socket in its upper end for the reception of said reduced lower end portion of the standard, and a work supporting member vertically adjustable on said standard, and a clamp pivotally connected with said supporting block. 80

5. A jack comprising a base having a seat thereon, a wrench having its fixed jaw rigidly mounted on and secured to said seat and having a shank portion, a movable wrench jaw having a shank portion guiding on the shank portion of the fixed jaw for rectilinear movement, means for effecting movement of said jaw and its shank toward and from said fixed jaw, and a jack standard detachably secured to said movable jaw at the end of the standard and intermediate of the length of the standard to said shank for movement therewith. 85

6. A jack comprising a base having a U-shaped clamping member pivotally mounted thereon for swinging movement about an axis parallel with and above its bottom face, a wrench having a fixed jaw rigidly secured

to said base and having a shank extending therefrom, a movable jaw having a shank guided upon said first shank for rectilinear movement, a jack standard secured to said movable jaw at the end of the standard and intermediate of the length of the standard to said shank for rectilinear movement therewith, and means for effecting relative movements between said fixed jaw and base and 5 said movable jaw and its attached jack standard.

7. A jack comprising a base plate having a jaw seat thereon, a hinged extension foot at one edge and a U-shaped clamping member pivotally mounted thereon at its opposite edge to swing about an axis parallel with and above the bottom face of the base, a wrench having its fixed jaw mounted on and rigidly held on said jaw seat and having a projecting shank, a second and movable jaw 15 having a shank guided on said first shank for rectilinear movement, means for effecting relative rectilinear movement of said jaws, and a jack standard secured to said second and movable jaw for movement therewith.

8. A jack comprising a base having a recessed seat therein, a screw adjustable wrench having the head of its fixed jaw crowned to 20 conform to and fit in said seat and having its shank upstanding therefrom, with co-operating means on jaw and seat for rigid interconnection thereof, a movable jaw having a tubular shank upstanding from its head 25 and embracing and vertically movable upon the shank of the fixed jaw, a jack standard demountably affixed to the shank and head of said movable jaw of said wrench for movement therewith, and means for engaging a support connected to said base and elevated 40 above the line of its bottom surface.
